DOG BED

Ruth S. Frazin, Yonkers, N. Y.

Application December 2, 1953, Serial No. 27,867

Term of patent 7 years

(Cl. D12—2)

To all whom it may concern:

Be it known that I, Ruth S. Frazin, a citizen of the United States of America, residing at 1080 Warburton Avenue, Yonkers 3, New York, have invented a new, original, and ornamental Design for a Dog Bed, of which the following is the specification, reference being had to the accompanying drawing, forming part thereof.

I claim:

The ornamental design for a dog bed, substantially as shown.
